Application January 21, 1959, Serial No. 54,261

Term of patent 14 years

(Cl. D72—1)

FIG. 3

FIG. 4

FIG. 2

Fig. 1 is a front elevational of an alarm box embodying my new design, the rear being substantially plain;

Fig. 2 is a side elevation thereof;

Fig. 3 is a top plan view thereof; and

Fig. 4 is a fragmentary perspective view of the upper portion of the front and side of the box.

The characteristic features of my design reside in the portions shown in full lines.

I claim:

The ornamental design for an alarm box, substantially as shown and described.
